TERMITES SHIELD

James D. Tennison, Memphis, Tenn.

Application June 24, 1938, Serial No. 215,673

4 Claims. (Cl. 72—0.5)

This invention relates to building construction and more particularly to termite shields incorporated in buildings constructed at least partly of wood or material similarly susceptible to termites.

Prior to my invention various expedients have been resorted to in order to prevent disintegration of wooden portions of a building which disintegration may be caused by termites. Buildings which are particularly susceptible to destruction by termites are those having no cellars with wooden portions directly contacting the ground. Treating the wood with certain poisons has been found to alleviate the situation somewhat; however, in time even the wood so treated will be destroyed should termites be present. It has further been proposed that masonry foundations be utilized and the wooden floor rafters be supported at quite some distance above the ground, say 18 inches to three feet. While termites do not fly, yet they can reach wooden portions of a building by climbing up the sides of a concrete wall and proceed to destroy wooden elements such as floor joists.

After some experimentation it has been found that if the wooden elements are kept above the ground a distance of more than twelve inches, say eighteen inches, the termites cannot travel directly from the ground to these wooden elements. In order to prevent the termites from reaching the wooden elements via the masonry foundation, metal baffles have been designed which are effective in preventing the termites from reaching the wooden elements supported above these baffles. The generally accepted baffle comprises preferably a metallic sheet having corrosion resisting properties which projects horizontally at least two inches from a side of a vertical foundation wall and then is bent at a forty-five degree angle downwardly, the bent portion projecting approximately two inches.

As foundation walls for dwellings are usually of greater running length than standard size metal sheets, tight joints are necessary between units of termite shield material. It has been proposed that these joints be affected by soldering, which is a relatively costly process.

It is an object of my invention to prove termite shields of simple design which may be readily fabricated en masse and which are effective in baffling the travel of termites.

It is a further object of the invention to provide sectional termite shields which permit of ready assembly.

Other objects and the nature and advantages

of the invention will be apparent from the following description taken in conjunction with the accompanying drawing, wherein:

Fig. 1 is a view in perspective of the simplest form of termite shield giving protection on but one side of a foundation wall;

Fig. 2 is a view in perspective of a termite shield giving protection on the inside and outside of a foundation wall;

Fig. 3 is a view in perspective of a unitary termite shield for protecting a pier;

Fig. 4 is a view in perspective of a sectional termite shield for use at the corner of a foundation and giving protection on but the inside wall thereof;

Fig. 5 is a sectional termite shield for use in connection with those portion of foundation walls which involve a T-junction;

Fig. 6 is a view in perspective of a sectional termite shield to be used at the corner of a foundation;

Fig. 7 is a sectional view of a foundation wall with the termite proofing in place;

Fig. 8 is a sectional view illustrating a tight joint effected by the ends of two sectional shields;

Fig. 8a is a sectional view of a tight joint involving two sectional shields and a connector.

Fig. 9 is a view in perspective of a shield connector;

Fig. 9a is a view in perspective of a modified form of connector;

Fig. 9b is a fragmentary sectional view similar to Figs. 8 and 8a of the connector illustrated in Fig. 9 and a pair of sheet metal termite shield sections associated therewith; and

Fig. 10 is a perspective view of a sectional termite shield for use in connection with a foundation wall having a projecting portion.

Referring to Fig. 1, the termite shield 20 comprises a horizontal portion 21 and a bent baffle 40 portion 22 formed integral therewith. This arrangement permits of ready fabrication in a simple stamping machine and will prevent the travel of termites vertically when this baffle is properly applied to the foundation wall as illustrated in Fig. 7, for example. The termite shield 20 is arranged to give protection either on the inside of the foundation wall or on the outside of the foundation wall depending on which side the bent portion 22 projects. If it projects on the inside of the foundation wall, it will give protection on that side and vice versa. Protection is most necessary on the inside of the foundation wall for this side is generally inaccessible and the first warning that termites are attacking the wooden

elements of the building is usually received too late; that is, when these wooden elements have been so eaten away that they no longer effect the proper support. The outside foundation wall is usually capable of periodic observation and any termite action may soon be disrupted. However, for best protection, a termite shield as illustrated in Fig. 2 should be used.

The termite shield 30, illustrated in Fig. 2, 10 comprises a horizontal portion 31 and two bent baffle portions 32 which are at an angle of forty-five degrees from a projection of the horizontal portion. With the baffle plate 30 in place as illustrated in Fig. 7 the horizontal portion 31 15 should project from the foundation wall 33, a distance of at least two inches, and the bent portion 32 should project angularly at least a distance of two inches to effect the proper baffling action, whereby termites may not travel from 20 the ground 34 to the wooden joists 35.

The shield 40 illustrated in Fig. 3 is a complete unit for use in connection with supporting piers or the like and comprises a horizontal portion 41, and angular portions 42 with corner portions 25 43 formed as shown to reinforce and take up the material when it is fabricated.

The termite shield 50 illustrated in Fig. 4 comprises a horizontal portion 51, bent portions 52 and end portions 53 so formed as to permit ready 30 assembly with similar sectional shields for eliminating the necessity for soldering or otherwise effecting the proper joint between sections of shields. The precise configuration of the end portion 53 is illustrated in Fig. 8 and will be later 35 explained in more detail.

Referring to Fig. 5 a termite shield sectional unit 60 is generally T-shaped to correspond with the configuration of certain portions of foundation walls and comprises a horizontal portion 61, 40 bent portions 62, and end portions 63 similar to the end portions 53 in Fig. 4 and are designed to interlock as will be later described.

The shield 70 illustrated in Fig. 6 is to be utilized in connection with corners formed by foundation walls and comprises a horizontal portion 71, bent portions 72, corner portions 73 similar to the corner portions 43 illustrated in Fig. 3 45 and end portions 74 similar to those illustrated in Figs. 4 and 5.

The shield 80 illustrated in Fig. 10 comprises a T-shaped horizontal portion 81, angularly disposed bent portions 82, corner portions 83 similar to the corner portions 73 in Fig. 6, and end portions 84 similar to those illustrated in Figs. 4, 5 and 6. This shield section 80 is to be utilized along a run of foundation wall having a slight projecting portion corresponding with the leg 81a of the horizontal portion 81.

In Fig. 8 a pair of sectional units 90 having 60 end portions 91 which are similar to the end portions 53, 63, 74 and 84 are shown in interlocking position to effect a tight joint such as is necessary to prevent termites from passing therethrough. The end portions 91 are generally S-shaped, the legs 92 of the lower portion of the S almost contacting each other as shown, whereby the necessary tight joint is effected. When one unit is slipped into the other a clamping action takes place which may be more pronounced 65 when a load is applied thereabove such as for example additional foundation wall or other building elements.

When the termite shields take the form illustrated in Figs. 1 and 2, the connecting unit such 70 as is illustrated in Figs. 9 and 9a may be used in

conjunction therewith. In Fig. 9 a connector 100 involving an S-shaped section is illustrated on end. Two sectional termite shields 20 such as is illustrated in Fig. 1 may be utilized in connection therewith, one shield being inserted into 5 the U-shaped portion 101 and the other into the U-shaped portion 102 of the connector whereby a relatively long continuous shield is effected having a tight joint. In Fig. 9a another form 10 of connector 110 is similarly illustrated and is adapted to receive sectional shields within the U-shaped portions 111 as illustrated in section in 15 Fig. 8a. In this case the joint effected in the arrangement illustrated in Fig. 8a by the connector 110 will similarly be tight as a similar clamping occurs which is increased by any load 20 imposed on the shields as is more or less inevitable in conventional building construction as already explained.

It will be obvious to those skilled in the art 25 that various changes may be made in this device without departing from the spirit of the invention and therefore the invention is not limited to what is shown in the drawings and described in the specification but only as indicated in the 25 appended claims.

I claim:

1. In a built-up termite shield, a plurality of sheet metal sections each having a generally horizontal planular area and a downwardly bent area 30 extending from said first area, said sections having interlocking male and female portions, said male and female portions being formed to resiliently interlock when the sections are assembled, said female portion resiliently engaging said male portion on at least two sides and co-extensively throughout the generally planular area and the downwardly bent area, said male and female portions arranged to readily slidably engage each other continuously and transversely of said 40 generally planular area and said downwardly bent area to form a termite-proof joint, whereby a built-up termite shield of relatively great length may be rapidly evolved on location without the use of special tools, equipment, or other 45 materials.

2. In a built-up termite shield, a plurality of sheet metal sections each having a generally horizontal planular area and a downwardly bent area extending from said first area, said sections 50 having interlocking male and female portions each comprising S formations in cross section with the bottommost generally horizontal portion of the S of substantially greater length than normal, said male and female portions being formed 55 to resiliently interlock when the sections are assembled with the bottommost portion of the S shaped cross section of one sheet metal section inserted above the corresponding bottommost portion of the S shaped cross section of the adjacent sheet metal section and underneath the central portion of the S shaped section of the said latter sheet metal sections to form a resilient interlock with said female portion resiliently engaging said male portion on two sides and co-extensively 60 throughout the generally planular area and the downwardly bent area, said male and female portions arranged to readily slidably engage each other continuously and transversely of said generally planular area and said downwardly 65 bent area to form a termite-proof shield of relatively great length may be rapidly evolved on location without the use of special tools, equipment, or other materials.

3. In a built-up termite shield, two sheet metal 70

5 sections each having a generally horizontal planar area and a downwardly bent area extending from said first area, a connector for said sheet metal sections having oppositely disposed resilient female engaging portions located in the same general plane on each side which extend co-extensively and transversely of said generally horizontal planar area and downwardly bent area of each of said sheet metal sections, the female 10 portions resiliently engaging the ends of said sheet metal sections co-extensively throughout the generally planar area and the downwardly bent area of each, said sheet metal section ends and said female portions arranged to slidably engage each other continuously and transversely of said generally planar area and said downwardly bent area to form a termite-proof joint, whereby a built-up termite shield of relatively great length may be rapidly evolved on location without the use of special tools, equipment, or 15 other materials.

4. In a built-up termite shield, two sheet metal

5 sections each having a generally horizontal planar area and a downwardly bent area extending from said first area, a connector having a generally S shaped cross section for said sheet metal sections having oppositely disposed vertically superimposed resilient female engaging portions extending co-extensively and transversely of said generally horizontal planar area and downwardly bent area of each of said sheet metal sections, the female portions resiliently engaging the 10 ends of said sheet metal sections co-extensively throughout the generally planar area and the downwardly bent area of each, said sheet metal section ends and said female portions arranged to slidably engage each other continuously and 15 transversely of said generally planar area and said downwardly bent area to form a termite-proof joint, whereby a built-up termite shield of relatively great length may be rapidly evolved on location without the use of special tools, equipment, or other materials. 20
